UNITED STATES PATENT OFFICE.

BRANDO MARCH, OF DELMONT, PENNSYLVANIA.

PENDANT-CORD SWITCH.

Application filed April 7, 1922. Serial No. 550,397.

To all whom it may concern:

Be it known that I, BRANDO MARCH, a citizen of the United States, residing at Delmont, in the county of Westmoreland and State of Pennsylvania, have invented new and useful Improvements in Pendant-Cord Switches, of which the following is a specification.

This invention relates to electrical devices, particularly to switches, and has for its object the provision of a novel switch designed primarily for use in connection with pendant cords used in connection with drop-lights or the like, the switch being of very simple construction and being easily operable whereby the current may be cut off when so desired.

An important object is the provision of a switch of this character which entirely eliminates the necessity for the employment of the ordinary switches and which will be much neater in appearance as it may be made very small and attractive.

Another object is the provision of a switch of this character in which the construction is so simple that repairs or replacement of a worn part may be easily made by even an unskilled person and without the use of any elaborate tools.

An additional object is the provision of a switch of this character which will be very simple and inexpensive in manufacture, highly efficient in use, positive in action, durable in service and a general improvement in the art.

With the above and other objects and advantages in view, the invention consists in the details of construction, to be hereinafter more fully described and claimed, and illustrated in the accompanying drawings, in which:

Figure 1 is a side elevation of the switch.

Figure 2 is an elevation taken at right angles to Figure 1.

Figure 3 is a longitudinal sectional view showing the switch in circuit breaking position.

Figure 4 is a similar view showing the parts in circuit making or closing position.

Figure 5 is an end view.

Figure 6 is a cross sectional view.

Figure 7 is an elevation of one side of the body member.

Figure 8 is an elevation of the opposite side.

Referring more particularly to the draw-

ings, I have shown the device as comprising an elongated body 10 formed as a strip of insulating material upon the central portion of one side of which is secured a metallic plate 11 which carries two binding screws 12, one of which is adapted for connection with a line wire 13 and the other end of which is adapted for connection with a wire 14 which leads to the drop light or other electric appliance.

Located upon the opposite side of the body 10 near the ends thereof are metallic plates 15 which are held in position by means of screws 16 and which carry binding screws 17, one of which is adapted for connection with a line wire 18 and the other of which is adapted for connection with a wire 19 leading to the drop light or other electric appliance to be energized. Formed at the side edges of the confronting ends of the metallic plate 15 are retaining flanges 20 within one pair of which is slidably mounted a metallic plate 21 adapted to be engaged beneath the other pair of flanges. This plate carries a shank 22 upon the free end of which is mounted an operating button 23.

The above described parts are located within an elongated sleeve 24 of insulated material which is provided with a slot 25 opening out at one end and which is provided for the accommodation of the shank 22.

The body member and associated parts together with the sleeve 24 is inclosed within a casing consisting of a shell member 26 which is provided at one end with a pair of holes 27 for the passage of the line wires 13 and 18 and which is provided near its other end with an elongated slot 28 for the accommodation of the operating button 23 during the movement thereof. One end of the shell member 26 is formed with a reduced extension upon which is engaged a second shell member 29 which has one end closed and provided with a pair of holes 30 through which pass the wires 14 and 19 leading to the electric appliance. The opposite end of this shell member 29 is formed with a lug 30 which fits within the open end of the slot 28 as shown.

Assuming that the device has been constructed and assembled as above described, when the switch is in normal or circuit breaking position, the operating button 23 is disposed at one end of the slot 28 in the shell member and the sliding plate 21 is retracted

- from engagement with the overhanging flanges on the most remote plate 15. When the parts are in this position, it will be seen that current cannot flow from the line wires 5 to the electric appliance. In order to close the circuit it is merely necessary that the operator push upon the button 23 with his thumb and thereby move the slideable plate 21 into engagement with the overhanging flanges of the farther plate 15 so as to bridge the gap between the two plates. When this is done the button 23 will be disposed at the other end of the slot 28. In actual practice it may be found advisable to provide the 10 shell members with legends "off" and "on" which are located adjacent the ends of the slot and which will apprise the operator whether or not the switch is in circuit making position.
- 15 20 From the foregoing description and a study of the drawing it will be apparent that I have thus provided a simply constructed and consequently inexpensive switch which is adapted for use in connection with drop lights, floor lamps, electric table appliances and in fact all such apparatus as is used in the household. Owing to the fact that all the working parts are entirely disposed within a shell of insulated 25 material, it is apparent that this device may be operated with perfect safety and without any danger whatever of receiving a shock. Another feature of advantage is that the device will be extremely neat in appearance 30 as it may be made very small. Owing to the simplicity of the construction and the fewness of the parts it is apparent that there is nothing to get out of order and that the device should consequently have a long life 35 and satisfactorily perform all the functions for which it is intended.
- 40 While I have shown and described the preferred embodiments of the invention, it is of course to be understood that I reserve the right to make such changes in the form, construction and arrangement of parts as will not depart from the spirit of invention or the scope of the subjoined claims.
- 45 Having thus described the invention, what 50 is claimed is:
1. A switch of the character described comprising an elongated body of insulating material, a metallic plate secured upon one side of said body and carrying binding 55 screws, a pair of metal plates secured upon the opposite side of the body and carrying binding screws, the inner ends of said pair of plates being formed at their side edges with overhanging flanges constituting guides, a plate member slidably engaged within said guides and having an operating button. 60
- 65 70 75 80 85 90 95 100 105 110 115
2. A switch of the character described comprising an elongated supporting body of insulating material, a metal plate secured upon one side thereof and carrying binding screws, a pair of metal plates secured upon the opposite sides of said body in spaced end to end relation and carrying binding screws, guide means at the inner ends of said pair of plates, a slideable plate engaged within said guide means and adapted to bridge the space between said pair of plates, a shank extending from said slideable plate and terminating in an operating button, an elongated tubular sleeve engaged exteriorly upon said body and formed with a longitudinal slot opening out at one end for the accommodation of said shank, and an enclosing shell disposed in encircling relation to said sleeve and formed of separable sections, said shell being formed with a longitudinal slot for the accommodation of said button and having its outer ends closed except for the provision of pairs of holes for the passage of wires to connect with said binding post or screws.
3. A switch of the character described comprising an elongated body of insulating material, a metallic plate secured upon one side of said body and carrying binding screws, a pair of metallic plates secured upon the opposite side of the body and carrying binding screws, said pair of plates being formed at their adjacent ends with guides, a plate member having an operating button and slideable within the guides on one plate and adapted to engage within the guides on the other one of said pair of plates, and an enclosing shell for said body having a slot permitting operation of said button.
4. A switch of the character described comprising an elongated body of insulating material, a metallic plate secured upon one side of said body and carrying means for connection with wires, a pair of metallic plates secured upon the opposite side of the body and provided with binding means for wires, the inner ends of said pair of plates being formed at their side edges with overhanging flanges constituting guides, a plate member slidably engaged within said guides and having an operating button.
- In testimony whereof I affix my signature.
- BRANDO MARCH.
